US00D951676S

(12) **United States Design Patent** (10) **Patent No.:** **US D951,676 S**
Zheng (45) **Date of Patent:** **** May 17, 2022**

(54) **PILLOW AND EYE MASK KIT**

(71) Applicant: **SHENZHEN PICTET FINO TECHNOLOGY CO., LTD**, Shenzhen (CN)

(72) Inventor: **Junsheng Zheng**, Shenzhen (CN)

(73) Assignee: **SHENZHEN PICTET FINO TECHNOLOGY CO., LTD**, Shenzhen (CN)

(**) Term: **15 Years**

(21) Appl. No.: **29/780,186**

(22) Filed: **Apr. 22, 2021**

(51) LOC (13) Cl. **06-09**

(52) U.S. Cl.

USPC **D6/601**; D16/309

(57)

CLAIM

The ornamental design for a pillow and eye mask kit, as shown and described.

DESCRIPTION

FIG. 1 is a perspective view of a pillow and eye mask kit showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the pillow and eye mask kit.
